UNITED STATES PATENT OFFICE

2,116,035

SLUG CASTING MACHINE

Richard R. Mead, Queens Village, N. Y., assignor
to Mergenthaler Linotype Company, a corpora-
tion of New York

Application December 10, 1936, Serial No. 115,089

48 Claims. (Cl. 199—50)

This invention relates to slug casting machines, such as linotype machines of the general organization represented in United States Letters Patent to Frolander, No. 1,971,400, wherein circulating matrices and expandable spacebands are composed in line by the manipulation of a keyboard, the composed line presented to the face of a slotted mold and between a pair of line clamping jaws, the jaws moved relatively one toward 10 the other to quad the line at one end, or each toward the other for quadding the line at both ends, the mold thereafter moved forwardly into contact with the composed line for the casting of a type bar or slug, and the matrices and spacebands subsequently separated and returned by 15 the distributing mechanism to the magazines from which they started.

More particularly, the present improvements contemplate a machine of this character which 20 will facilitate the casting of slugs for use in printing return addresses on envelopes.

As a rule, the return address on an envelope consists of three or four printed lines varying in 25 length but centered with respect to each other, and with the longest line spaced at a given distance from the left end of the envelope. The casting of slugs of this character in commercial machines is attended with considerable difficulty involving slow, tedious and painstaking work. 30 This difficulty, as will be appreciated by those familiar with "linotype" composition, comes from the fact that the slug bearing the longest type line requires to be quadded at the right, while the lugs bearing the shorter type lines require to 35 be quadded both at the left and right in such manner that the shorter type lines will be centered with reference to the longest quadded type line. While the quadding and centering devices with which the commercial machines are sometimes equipped permit the casting of slugs quadded at either or both ends of the type line, these devices nevertheless, as now constituted, are 40 not susceptible of operation to produce the desired result.

45 The machine equipped with the present improvements is like that shown in the Frolander patent, in the respect that the two line clamping jaws are mounted on movable supports actuated through two distinct trains of connections from 50 a vertically movable rod controlled directly from the main shaft of the machine, provision being made for connecting both jaw supports to the rod, so that they can be moved equidistantly toward each other until arrested by the contact of 55 their respective jaws with the opposite ends of

the composed line (for centering), and for connecting the right hand jaw support to the vertically movable rod, so that the right hand jaw can be moved toward the left hand jaw until arrested by contact with the end of the composed line for quadding at the right, the conditioning of the machine for centering or quadding being effected through the medium of a horizontal slide locatable in one position or another, depending upon whether a centering or a quadding 10 operation is desired.

The improved machine, however, contemplates certain modifications in the Frolander machine which will permit the casting of slugs in groups constituting each a return address, and with the 15 first or longest line of each group quadded at the right and the other or shorter lines of the group quadded at both ends in a manner to center such lines with respect to the longest quadded line. When the slugs are thus cast, the first line of the group will have a fixed location 20 with reference to the left end of the slug, so that the group of slugs when locked up in the printing form will print the return address on the envelope with the longest line the proper distance 25 from the left end thereof and with the shorter lines centered with respect thereto.

The conditioning of the improved machine for casting slugs in groups of the above character is effected automatically according to a prearranged 30 sequence. This automatic conditioning of the machine is effected through the medium of a star wheel actuated from the first elevator and having a step by step movement. The star wheel acts to locate the horizontal conditioning slide in its 35 different positions and, depending upon the design of the star wheel, which is selected according to the number of lines in the return address, will condition the machine automatically for one quadding operation at the right end of the line 40 and for any desired number of subsequent centering operations.

In the improved machine, the right hand jaw is movable with respect to its jaw support and after the longest line, which is quadded at the right, has been cast, the jaw support is returned to its normal position, but the right hand jaw is held stationary in its quadding position by mechanism including locking devices located on the fixed vise frame. In the next cycle, the machine is automatically conditioned for a centering operation, through the medium of the star wheel, previously alluded to. In addition to conditioning the machine for a centering operation, however, the conditioning slide performs two ad- 45 50 55

ditional functions: First, it releases a series of spring-pressed pawls mounted in the right hand jaw support and allows them to engage ratchet teeth on the right hand jaw to lock the jaw to its 5 jaw support and maintain them in the relative positions which they then occupy, i. e., with the jaw in its quadding position and the jaw support in its normal position. Second, the conditioning slide releases the locking devices on the 10 vise frame, so that the jaw and its supporting block may be reciprocated as a unit. Consequently, when the second line of the return address is presented to the mold, it will be centered with respect to the line previously cast, since 15 both jaws will move equi-distantly toward each other until arrested by contact with the opposite ends of the line but from initial positions coincidental with the ends of the quadded line cast in the previous machine cycle. As long as the 20 machine is conditioned for centering, the right hand jaw is locked to its jaw support in the relative position, determined by the first or longest line of the group during the quadding of such line. Consequently, all of the other lines of the 25 group will be centered with respect to such quadded line.

At the beginning of the machine cycle in which the first slug of the next group of slugs is cast, the pawls will be disengaged from the right hand 30 jaw and the latter is allowed to return to its original or normal position. Thereafter, the previous sequence of operations is automatically repeated for the new group of slugs.

As a subsidiary feature of the present invention, an arrangement has been provided, whereby the slugs for the return addresses may be of the fudge variety, i. e., formed with bevelled ends by which they are clamped in a fudge box or a printing cylinder. Heretofore, in casting 35 such slugs, the fudge molds have their body, cap and liner portions formed with bevelled recesses at the ends of the mold slot, and the line clamping jaws are provided with complementary bevelled blocks arranged to fit the recesses and close 40 the mold slot at its ends during the slug casting operation, thus requiring that the line clamping jaws have a fixed location during each casting operation. In the present arrangement, the same 45 type of fudge mold is used, but the bevelled blocks, instead of being carried by the line clamping jaws, are secured to the fixed vise frame, although they are backed up by the line clamping jaws through a tongue and groove connection which permits the jaws to move longitudinally 50 with respect thereto. With this arrangement, the line clamping jaws may assume any position, as determined by the length of the line being cast and the conditioning of the machine (i. e., for quadding or centering), while the bevelled 55 blocks will always be located in the proper positions for closing the mold slot at the ends to form the bevelled portions of the slugs.

Another feature of the present invention deals with the mechanism for transferring the composed line through the intermediate channel to the line transporter or first elevator which presents the composed line to the mold. In the regular commercial machine, the line delivery carriage is equipped with a pair of depending fingers, between which the line is located by the assembler elevator prior to its transfer, and the right hand finger is fixed to the carriage and during transfer pushes the line to the left until it picks up the left hand finger, the latter being 60 movable on the carriage. With such an ar-

rangement, the line is presented in casting position with its trailing end adjacent the right hand jaw, the latter always being located in a definite normal position. With the present improvements however, it will be recalled that the right hand jaw, prior to the casting of a line to be centered, may be located to the left of its normal position, and thus would, unless otherwise provided for, interfere with the presentation of subsequent lines to the mold. Accordingly, provision is made for the presentation of the composed lines to the mold with the leading end thereof adjacent the left hand jaw. No interference between the lines and the right hand jaw can therefore occur, since for the first or 10 longest line of a group, the right hand jaw will be in its normal position of maximum separation and, since all of the subsequent lines in the group will be shorter than the first and consequently will clear the right hand jaw, even 15 though it stands to the left of its normal position.

Referring to the drawings:

Figs. 24 to 30 are diagrammatic views, showing the different locations of the jaws and their respective jaw supports during a plurality of machine cycles in which the group of slugs bearing a return address are cast.

The matrices X and expandable spacebands Y are composed in line in the assembler A (Fig. 1) under the restraining influence of a line resistant (not shown) which can be set for lines of different length, all in the usual way. After the line has been composed, the assembler is raised to position the line between the fingers of the line delivery carriage B, which thereupon moves to the left (and in doing so inaugurating the operation of the machine) and transfers the composed line through the intermediate channel B¹ into the vertically movable transporter or first elevator C slidably mounted in the vise frame D. Upon receiving the line, the first elevator immediately descends to position it between the left hand jaw E and the right hand jaw F and in front of the slotted mold G, which latter then advances from the rear and into contact with the line and the two clamping jaws for the slug casting operation, the line, prior to casting, being aligned and justified in the usual way when the machine is being operated under the usual conditions. After the slug has been cast, the mold is carried from its horizontal casting position to a vertical ejecting position by a three-quarter rotation of the mold disc, the first elevator in the meantime being raised to deliver the composed line to the matrix and spaceband distributing devices and finally coming to rest in its original or line receiving position.

The machine is equipped for "quadding" and "centering" and, to this end, the jaws are mounted for movement in the vise frame in the customary manner, being carried by supporting blocks E¹ and F¹ slidably in suitable guideways formed in the vise frame. The two jaws E and F are movable toward and from each other by a periodically operated part in the form of a vertically movable rod H, which may be connected at its upper end to the respective jaws E and F through the medium of two similar but oppositely disposed bell crank levers E² and F², pivoted at

E³ and F³, to the vise frame D, the longer arms of said levers being connected by short links E⁴ and F⁴ to the jaw supports respectively, and the shorter arms of said levers being arranged for connection to the rod H. According to this arrangement, when the rod H is moved downwardly from its uppermost position (which is its normal position of rest), it will move the two jaws equidistantly toward each other (assuming both to be connected to the rod) until they contact with the opposite ends of a composed line which has previously been positioned between them and, when the rod is moved upwardly for restoration to its position of rest, it will, in like manner, move the jaws equi-distantly away from each other to return them to their original positions of maximum separation, provision being made for lines varying in length by varying the extent of movement of the rod H, all as more fully described in the Frolander Patent No. 1,971,400, reference to which may be had for a more detailed description of the parts.

Provision is made for connecting and disconnecting the rod H with and from the jaws E and F, and for this purpose (see Figs. 1, 2 and 3) there is mounted on the rod at its upper end, for rotation only, a grooved collar H¹ for engagement with diametrically opposed pins e protruding inwardly from the extremities of the horizontal arms of the actuating levers E² and F² for the jaws E and F, respectively. In the commercial machine, the upper portion of the grooved collar H¹ presents a plurality of segments which can, by the rotation of the collar, be arranged selectively to cooperate with either one or both of the jaw operating levers E² and F², for quadding at either end of the line, or for centering, or disconnected from both levers when the machine is to be used for regular operation. With the improved attachment however, only two positions of adjustment of the collar H¹ are used, one wherein the lever F² actuating the right hand jaw only is connected to the vertically movable rod H for right hand quadding, and the other wherein both jaw actuating levers E² and F² are connected to said rod for centering.

The collar H¹ is moved to its various positions of adjustment by a slide J arranged in horizontal guideways J¹ mounted at the front of the vise frame and operating through the medium of a series of rack teeth formed on a block J² carried by the slide, a pinion H² meshing with the rack teeth, and a pair of bevelled gears (not shown), one formed at the top of the collar, and the other on a short fore-and-aft shaft to which the pinion H² is fixed. The slide is urged toward the left by a tension spring J³ fastened at the left end thereof and having an anchorage in the vise frame. When the slide is in its leftmost position, the machine is conditioned for a centering operation; whereas, when the slide is moved to the right, the machine is conditioned for quadding with the right hand jaw, both positions of adjustment (see Fig. 1) being indicated by markings on the upper horizontal guide J¹ labelled, respectively, "Cent.", indicating centering, and "Quad.", indicating right hand quadding, and a cooperating pointer carried by the slide J.

As previously stated, the present improvements contemplate the casting of slugs in groups constituting each a return address, and wherein the first or longest line of each group is quadded at the right, and the other lines of the group centered with respect to the longest line. The casting

of the first line of a group involves a true quadding operation and the conditioning of the machine accordingly, i. e., the adjustment of the conditioning slide J to its rightmost position. Although the casting of subsequent lines of a group do not involve a true centering operation (that is, insofar as the mold slot is concerned, since with regard to the mold slot, these lines are located asymmetrically with respect to the center line thereof in a position depending upon the length of the longest line), the machine is nevertheless conditioned as if it were a true centering operation, i. e., both jaws are connected for movement by the vertically movable rod H which, as mentioned previously, involves the adjustment of the conditioning slide J to its leftmost position.

The positioning of the conditioning slide J is effected automatically, the mechanism for this purpose including a star wheel K rotatably mounted on a stud K¹ projecting forwardly from the vise frame and arranged to be rotated with a step by step movement in a clockwise direction (see Figs. 1 to 4). The mechanism also includes a bell crank lever J⁴ fulcrumed on the vise frame at the front and having its lower arm pivotally connected to the conditioning slide J at the left end of the latter, the upper or horizontal arm of said lever being adapted to cooperate with prongs K² on the star wheel. According to this arrangement, as the star wheel K is moved to bring any of the prongs thereof into cooperative engagement with the lever J⁴, the latter will be actuated to move the conditioning slide to the right (Fig. 3); whereas, when such prong moves out of cooperative engagement with the lever, the conditioning slide will be moved to the left by the pull of the spring J³ (Fig. 1).

The step by step movement of the star wheel K is effected by a toothed ratchet wheel K³ formed at the inner end of a sleeve K⁴ rotatably mounted on the stud K¹ (Figs. 4, 6 and 7), and operated by a lever K⁵ through the medium of a pawl K⁶ pivotally mounted in the lever and spring-pressed into engagement with the teeth of the ratchet wheel. The lever K⁵ is freely mounted on the sleeve K⁴ of the ratchet wheel and is resiliently held in its normal or horizontal position against turning by a tension spring K⁷ connected to an arm K⁸ of said lever and anchored in the vise frame (Fig. 3). At the beginning of each machine cycle, a spring pressed pin C¹, mounted in the first elevator (see Figs. 1 and 4) immediately above the lever K⁵ when the parts are in normal position, will, as the first elevator starts to descend, engage a projection k formed in the end of said lever and turn it against the tension of the spring K⁷ from the position shown by the solid lines in Fig. 2 to the position shown by the dotted lines therein, and thus rotate the ratchet wheel K³ through an increment of one tooth with an equivalent rotation of the star wheel, the latter being connected to the ratchet wheel in a manner hereinafter described. As the first elevator continues to descend, the pin C¹ passes beyond the lever K⁵, allowing the latter to return to its normal position, which it does under the tension of the spring K⁷, retrograde movement of the ratchet wheel being prevented by another pawl K⁹ pivotally mounted on the vise frame and likewise spring-pressed into engagement with the teeth of the ratchet wheel. The projection k on the lever K⁵ is bevelled at the bottom to allow the pin C¹ to ride past the lever without interference during the ascent of the first elevator.

The ratchet wheel K³ is equipped with twelve teeth, and provision is made for changing the star wheels, so that different numbers of centered lines can be cast between each quadded line in order to accommodate return addresses composed of lines differing in number. Thus, there is shown in Figs. 6 and 7, merely by way of illustration, a combination star wheel which will permit the casting of one quadded line and two subsequent centered lines or one quadded line and eleven subsequent centered lines, the star wheel being formed with four prongs in one plane spaced at 90° intervals and one projection in another parallel plane for this purpose. The star wheel is demountably arranged on a sleeve K¹⁰, the inner diameter of which is somewhat larger than the diameter of the stud K¹ on which the sleeve is mounted, in order to accommodate a spring K¹¹ which reacts against a shoulder K¹² presented at the inner end of such enlarged portion and a head K¹³ with which the stud is formed at its outer end. The sleeve at its inner end is provided with a flat key-like protrusion K¹⁴ adapted to engage in one or another of a pair of different sized slots K¹⁵ and K¹⁶ formed in the sleeve K⁴ on which the ratchet wheel is formed and in the end thereof adjacent the star wheel. These slots are of different depths and are spaced apart at an angle of 90°. According to this arrangement, when the sleeve is turned to bring the protrusion K¹⁴ into register with the smaller slot K¹⁵, the star wheel will be in a position to locate the prong which provides for one quadding operation in every twelve in the path of the slide operating lever J⁴; whereas, when the sleeve is turned to bring the protrusion K¹⁴ into register with the larger slot K¹⁶, the star wheel will be in a position to locate the four pronged portion thereof, which provides for one quadding operation in every three, in the path of the lever J⁴. The protrusion K¹⁴ is held in the slots K¹⁵ and K¹⁶ by the spring K¹¹, previously referred to. The star wheel can be rendered entirely inoperative by pulling the sleeve out to the position shown in Fig. 7, in which case the machine will be conditioned for centering all lines. The star wheel is held in this latter inactive position of adjustment by a spring-pressed detent K¹⁷ in the head of the stud K¹ and which is adapted to engage in an annular recess K¹⁸ formed in the inner face of the sleeve K¹⁰ when in the position of adjustment referred to.

As previously stated, the star wheel K is demountably arranged on the sleeve K¹⁰ and is properly located and held in position by a U-shaped spring clamp K¹⁹, one leg of which is screwed to the star wheel, as at K²⁰, and the body portion of which seats in a longitudinal slot K²¹ extending from the star wheel outwardly to the end of the sleeve. The spring clamp has an enlarged outer portion K²² (Fig. 8) which seats in a cross slot K²³ arranged at right angles to the slot K²¹, previously referred to, this slot arrangement and form of clamp preventing any rotational or longitudinal movement of the star wheel with respect to the sleeve K¹⁰. In order to remove the star wheel, it is necessary only to pull the outer wider portion of the clamp out of the cross slot K²³, whereupon the star wheel can be removed from the sleeve and another one replaced thereon. In Fig. 9, a three-pronged star wheel is illustrated, which will condition the machine for casting one quadded line in every four. If desired, torsional strain can be removed from the spring K¹⁹ by providing the star wheel K in its inner cylindrical

face with a projection or feather K^{24} fitting into the slot K^{21} , immediately to the rear of the spring.

With the mechanism just described, it is obvious that the machine can be conditioned automatically to quad at the right end of a line and at both ends of the line according to a prearranged sequence in any given series of successive machine cycles.

As stated previously, each group of slugs, constituting a return address, consists of one slug with the line thereon quadded at the right and a plurality of slugs bearing shorter lines quadded at both ends in a manner such that the shorter lines will be centered with respect to the longest quadded line. The casting of the latter slugs is facilitated by making the right hand jaw F movable with respect to its jaw support F^1 and, after the jaw support F^1 has moved toward the left to effect the quadding of the longest line, the jaw F is locked against return movement in its quadding position by means on the vise frame, while the jaw support is allowed to return to its normal position. With the jaw and jaw support thus relatively located, mechanism is rendered effective, when the machine is conditioned for centering in the next cycle, to lock the jaw to the jaw support and then to release the lock which initially restrained the jaw in its quadding position in the first cycle. With the machine thus conditioned, and upon the operation of the quadding mechanism, the jaws E and F will move toward each other equi-distantly to quad the line at both ends, but as the initial position of the jaws for this operation was coincidental with the ends of the longest quadded line, subsequent lines will be centered with respect to such line and not with the mold slot as usual.

In order to permit relative movement between the right hand jaw F and its jaw support F^1 , the latter (see Figs. 16, 19 and 20) is formed with a portion F^5 offset rearwardly from the main portion of the support and at the top of which there is presented a tongue F^6 dove-tailed into a complementary groove formed in the bottom of the jaw, this arrangement serving to guide the jaw with respect to the jaw support during relative movement between the two. The jaw F is formed in its lower edge (Figs. 16 and 17) with ratchet teeth F^7 adapted to cooperate with corresponding teeth F^8 formed at the top of a series of three spring-pressed plunger pawls F^9 guided for vertical movement in complementally formed recesses F^{10} in the jaw support F^1 directly beneath the jaw. The three pawl arrangement permits finer adjustments of the jaw with respect to the jaw supporting block than could be obtained by a single pawl with ratchet teeth of the same size.

Normally the pawls F^9 are urged into engagement with the jaw F by springs f and, when so engaged, will lock the jaw against movement to the right relatively to the jaw support F^1 in any position the jaw is caused to assume. It will be noted, however, that the pawl arrangement is such that the jaw support can move to the right when the jaw is held against movement even though the pawls are active, the teeth on the pawls in such cases merely riffling over the teeth in the jaw. By moving the pawls downwardly out of engagement with the jaw, the jaw will be free for relative movement with respect to its jaw support.

The pawls F^9 are moved out of engagement with the jaw F by a horizontal bar F^{11} (Figs. 16 and 18) formed with a bevelled nose portion F^{12} arranged

to cooperate with complementary bevelled faces F^{13} presented at the bottom of recesses F^{14} formed in the pawls. The horizontal bar F^{11} is mounted for limited fore-and-aft movement in the jaw support F^1 by a pair of cylindrical studs F^{15} formed at the ends of the bar and slideable in holes F^{16} drilled in the jaw support for the purpose. The arrangement is such that, as the bar F^{11} is moved rearwardly, it will cam the pawls F^9 downwardly out of locking engagement with the jaw; whereas, when the bar is released, the pawls will move upwardly under the action of their respective springs into engagement with the jaw, locking it against relative movement to the right with respect to the jaw support, as previously described. Parallel movement of the bar F^{11} is insured by a U-shaped bail member F^{17} pivotally mounted on a horizontal shaft F^{18} in the jaw support and which is formed with rigid end portions F^{19} pivotally engaging in the cylindrical studs F^{15} .

The right hand jaw F is also formed in its front face (Figs. 13 and 17) with a series of rack teeth F^{20} which mesh with a pinion D^1 formed at the lower end of a short vertical shaft D^2 journalled in a bracket D^3 fixed on the vise frame. The shaft D^2 , at its upper end, is provided with another pinion D^4 meshing with teeth d formed on a large substantially circular plate D^5 mounted for free rotation on a vertical stud D^6 fixed in the base of the bracket D^3 , and which extends upwardly through a portion D^7 of the bracket that overlies the circular plate D^5 . This circular plate (see also Figs. 4 and 12) presents the teeth d on a portion only of its peripheral edge, the remaining portion of said edge being formed with a series of ratchet teeth d^1 adapted to cooperate with a series of three spring-actuated locking pawls D^8 guided in slots formed in a block D^9 arranged for limited fore-and-aft movement in the bracket D^3 , previously referred to. The block D^9 , as shown in Fig. 14, is formed with a base portion D^{10} , in which the spring-pressed pawls are seated, and a cap portion D^{11} screwed to the base portion and which acts to hold the pawls in place. The cap portion is slightly recessed above the pawls, as at D^{12} (Fig. 12a), so as to present a shoulder which acts to limit the movement of the pawls in a fore-and-aft direction in the block and is thickened at the center where it is drilled to receive one end of a compression spring D^{13} , which reacts between said block and the fixed bracket D^3 , which latter is likewise drilled to receive the other end of said spring, the spring tending to urge the block forwardly to move the pawls D^8 out of engagement with the ratchet teeth on the disc D^5 . The disc D^5 (see Figs. 12 and 13) is connected, through the medium of screws d^2 and an intermediate arcuate-shaped spacing member D^{14} , with a pulley D^{15} overlying the top portion D^7 of the bracket and, like the disc, mounted for free rotation on the vertical stud D^6 , so that actually the disc and pulley move as one. A spiral spring D^{16} extends around the pulley D^{15} , being anchored thereto at one end, and at its other end to a vertical post D^{17} fixed on the vise frame (see Figs. 1, 4 and 13).

According to this arrangement, when the jaw F moves toward the left during a quadding operation, it will, through the pinions D^1 and D^4 , rotate the disc D^5 in a clockwise direction against the tension of the spring D^{16} by an amount depending upon the extent of movement of the jaw. Should the block D^9 carrying the locking pawls D^8 be moved rearwardly to effect the engagement of

the pawls with the circular disc D⁵ before the jaw support F¹ starts its return movement, the jaw F, through the disc and pinions, will be locked in its quadding position, allowing the jaw support to return to normal position alone, as previously described. When the block D⁹ is moved forwardly to disengage the pawls D⁸ from the disc, the jaw F will be returned to its normal position with respect to its jaw support under the action of the spring D¹⁶, assuming, of course, that the locking pawls F⁹ in the jaw support are inactive, i. e., out of engagement with the teeth F⁷ on the jaw. However, should the locking pawls D⁸ not be rendered active during a casting cycle, the jaw, under the tension of the spring D¹⁶, will follow the return movement of the jaw support, maintaining, of course, its set position with respect to the jaw support if it has been locked in some position other than the normal one.

Assuming now that the operator desires to cast a series of return addresses, consisting of one long line and two shorter lines, a four-pronged star wheel will be selected. The first or longest line is transferred from the assembler A through the delivery channel B¹ to the first elevator C, which, of course, will be in its normal line receiving position, as shown in Fig. 1. As the first elevator descends to present the composed line to the mold, the star wheel K is rotated in a clockwise direction from the position shown in Fig. 1 to the position shown in Fig. 2, thereby adjusting the conditioning slide J to the right, which is the setting of the slide for right hand quadding, in the manner previously described. This adjustment of the slide J connects the right hand jaw support F¹, through its actuating lever F², with the vertically movable rod H, and simultaneously disconnects the left hand jaw support E from the vertically movable rod H.

In addition to conditioning the machine for right hand quadding, however, the slide J, when adjusted to the right, performs two other functions. First, through intermediate connections described below, it moves the horizontal bar F¹¹ associated with the locking pawls F⁹ rearwardly to effect the disengagement of the pawls from the jaw F, so that the right hand jaw will be returned to its normal position under the action of the spring D¹⁶, in the manner previously described, in the event the right hand jaw was located in some position other than normal, as a result of a previous casting operation.

The horizontal bar F¹¹ is actuated as follows. When the slide J is adjusted toward the right, it banks at its left end against an adjustable banking screw l threaded in the end of a horizontal arm L (see Figs. 10, 11 and 15) formed at the bottom of a lever L¹ hinged on a vertical shaft D¹⁸ mounted in a bracket D¹⁹ fixed to the vise frame. The lever L¹ has a long vertical body portion and is formed at its upper end with an arm L² extending at right angles to the lower arm L of said lever. The arm L² is connected to a lever L³, fulcrumed adjacent its center on the vise frame, through the medium of a link L⁴ pivotally connected to the lever L³ at its upper end, as at L⁵, and to the arm L² by a ball and socket joint L⁶. According to this arrangement, when the lever L¹ is turned in a clockwise direction, by the adjustment of the slide J to the right, the lever L³ is turned from the position shown in Fig. 15 to the position shown in Fig. 16 and, in doing so, will push the bar F¹¹ rearwardly to effect

the disengagement of the pawls F⁹ from the jaw F.

The second additional function performed by the conditioning slide J is the conditioning of mechanism which subsequently in the machine cycle renders the locking pawls D⁸ active to lock the jaw F in its quadding position. This mechanism (see Fig. 2) includes in part, a bell crank lever M pivotally mounted on the vise frame and located in its normal position by a banking pin M¹ against which the horizontal arm of the lever is resiliently held by a tension spring M² anchored in the vise frame. The mechanism also includes an L-shaped lever M³ arranged adjacent the bell crank lever M and likewise pivotally mounted on the vise frame. Like the lever M, the lever M³ is located in its normal position by a banking pin M⁴, against which the vertical arm of the lever is resiliently held by a tension spring M⁵ anchored to the vise frame. The mechanism further includes a pair of detents M⁶ and M⁷, one (the detent M⁶) being arranged behind the lever M³ in a small bracket M⁸ fixed to the vise frame (see Figs. 3^a, 10 and 11), and which serves also to guide the conditioning slide J, in front of which said detent is located, and the other (the detent M⁷) in a recess m formed at the lower end of an arm M⁹ pivotally mounted on the stud that supports the lever M³, the detent M⁷ being located immediately at the right of and in contact with the edge of the lever M³.

The detent M⁶ includes a cup-shaped element M¹⁰ arranged to seat in a recess M¹¹ formed in the slide J when the latter is in its leftmost position, a ball M¹² pressing against the lever M³ at the rear, and an intermediate spring M¹³ reacting between the cup-shaped member and the ball, and which exerts no pressure when the cup-shaped element M¹⁰ is seated in the recess M¹¹ in the slide.

The detent M⁷ includes a head portion M¹⁴ having its outer face conical in shape where it engages the lever M³, a reduced stem portion M¹⁵ integral with the head portion and which, at its rear end, is provided with an anti-friction roller M¹⁶, and a spring M¹⁷ reacting between the head portion and the base of the recess M⁸.

When the conditioning slide J is adjusted to the right to condition the machine for quadding right, the cup-shaped element M¹⁰ rides out of the recess M¹¹ in the slide, thereby placing its associated spring M¹³ under compression. At the same time, the slide J moves in back of the anti-friction roller M¹⁶ of the second detent M⁷, so as to lock the latter against rearward movement.

It will be recalled that the various conditioning functions of the slide J are effected immediately as the first elevator C starts to descend. The first elevator continues to descend to present the line in casting position between the line clamping jaws and, when the line is so located, the vertically movable rod H likewise descends, moving the right hand jaw support F¹, and consequently the jaw F, toward the left until it is arrested by contact with the end of the composed line. During this movement of the jaw, it will also be recalled that the circular disc D⁵ is rotated in a clockwise direction against the tension of the spring D¹⁶ through a distance determined by the extent of movement of the jaw.

After the line has been quadded, the casting operation follows, whereupon the first elevator starts to ascend to transfer the composed line

to the distributing mechanism. As the first elevator starts its ascent, and before any return movement of the jaw support F^1 has occurred, a spring-pressed pin C^2 in the first elevator engages a projection m^3 formed on the lever M , turning the lever against the tension of its spring M^2 in a clockwise direction from the position shown in Fig. 2 to the position shown in Fig. 3, it being understood that the projection m^3 is bevelled at the top so as not to interfere with the descent of the first elevator. As the lever M is thus turned, it engages the L-shaped lever M^3 , pushing the latter to the right. The lever M^3 , through the medium of the detent M^7 , which acts as a rigid interponent, by virtue of its conditioning by the slide J , moves the arm M^9 , in which the detent is carried from the position shown by the solid lines in Fig. 11 to the position shown by the dotted lines therein. This movement of the arm M^9 rocks the vertical shaft D^{18} in a clockwise direction through the medium of an arm M^{18} pinned to the shaft at its lower end and which is held resiliently against a banking screw M^{19} mounted in said arm by a tension spring M^{20} fastened to said arm and anchored in the lever L^1 .

As the shaft D^{18} is rocked, an arm M^{21} pinned at the upper end thereof (see Fig. 12) presses against the block D^9 which carries the locking pawls D^8 , moving said block rearwardly to effect the engagement of the pawls with the ratchet teeth on the disc D^5 , thus locking the disc and consequently the right hand jaw against movement. The pawls are retained in their active or locking position by the detent M^6 which engages in a recess m^1 formed in the rear face of the L-shaped lever M^3 , it being recalled that said detent is under compression when the conditioning slide J is in its rightmost position. Merely as a precaution in the event the detent M^6 does not act properly, a latch D^{20} is provided (see Figs. 12 and 13), hinged to the fixed bracket D^3 on the vise frame and which drops by gravity from the dotted line position shown in Fig. 13 to the solid line position shown therein, to engage in front of the block D^9 . The latch D^{20} acts to prevent any forward movement of the block D^9 which would permit the disengagement of the pawls D^8 from the disc D^5 .

After the right hand jaw F has been locked against movement in its quadding position as just described, the first elevator continues its ascent to the upper transfer level. The vertically movable rod H also ascends to restore the right hand jaw support F^1 to its normal position of maximum separation, but since the jaw is locked against movement, the jaw support will return alone. In connection with this return movement of the jaw, it might be helpful at this point to recall that during the machine cycle just completed, the lever L^3 , which effects the operation of the pawl disengaging bar F^{11} in the jaw support F^1 , remains active throughout. When the jaw support was moved to the left during the quadding operation, however, the bar F^{11} passed from under the influence of the lever L^3 and thus released the pawls F^9 but, when the jaw support is returned to its normal position at the conclusion of the quadding operation, the bar F^{11} is again moved rearwardly to disengage the pawls from the jaw as it comes again into engagement with the lever L^3 . For this purpose, the lever L^3 is formed at its lower end with a bevelled nose portion L^7 (see Fig. 18), which moves the bar F^{11} rearwardly with a camming action.

The second line of the group constituting the return address, and which is to be centered with respect to the longest line previously cast, is now transferred in the usual way to the first elevator C . The first elevator thereupon descends and, as it does so, rotates the star wheel K , moving the prong K^2 thereon (which, in the previous cycle, had actuated the slide operating lever J^4 to adjust the slide to the right) out of engagement with said lever and thus allowing the slide J to be adjusted to the left under the action of its associated spring J^3 . This adjustment of the slide J , through the rotation of the collar H^1 , connects both jaw supports E^1 and F^1 for operation by the vertically movable rod H through the medium of the actuating levers E^2 and F^2 .

Again the conditioning slide J performs two additional functions. First, its releases the pawl actuating bar F^{11} , since, as shown in Fig. 10, the slide J moves out of engagement with the lever arm L and thus frees the lever L^3 , which is then returned to its normal position (see Fig. 11) by the bar F^{11} as the spring-pressed pawls F^9 move upwardly into engagement with the right hand jaw under the action of their associated springs. Recalling now that the right hand jaw is still in the position in which it was arrested by the quadding of the line cast in the previous cycle and the jaw support F^1 in its normal position, these relative positions will be maintained by the pawls F^9 .

The operation of the pawls F^9 occurs during the first stage of movement of the slide J toward the left and, as the slide continues its movement, the cup-shaped element M^{10} of the detent M^6 will ride down into the recess M^{11} in the slide (see Fig. 10), thus releasing the L-shaped lever M^3 and allowing the latter to return to its normal position under the tension of the spring M^5 . The slide J also rides out of engagement with the anti-friction roller M^{16} of the detent M^7 , thus allowing the rock shaft D^{18} to be turned in a counterclockwise direction by the action of the spring M^{20} upon the arm M^{18} which, as will be recalled, is pinned to the rock shaft at its lower end. This rocking movement of the shaft D^{18} rotates the arm M^{21} at the upper end of the rock shaft to effect the lifting of the latch D^{20} (the arm M^{21} and the latch D^{20} being formed with complementary bevelled surfaces for this purpose), thereby releasing the block D^9 which carries the locking pawls D^8 and allowing the pawls to be moved out of engagement with the disc D^5 by the action of the spring D^{13} .

At this stage of the machine cycle, namely, immediately after the slide J has been adjusted to the left, the jaw F , as previously stated, will be locked to its jaw support F^1 , but will be unlocked from the vise frame and consequently free to move with the jaw support during the centering operation to follow.

The first elevator C continues its descent to present the composed line between the line clamping jaws. The vertically movable rod H descends to effect the centering operation, but now because of the relative position of the jaws, which are coincidental with the ends of the line cast in the previous cycle, the second line will be centered with respect to the line previously cast.

After the casting operation, the first elevator ascends to transfer the line for distribution and, as it does so, the levers M and M^3 are operated as before, but this operation will be an idle one, since the detent M^7 will just move rearwardly against the force exerted by its spring and without actu-

ating the locking pawls D⁸. Consequently, when the vertically movable rod H ascends to effect the return movement of the jaw supports to their normal positions, the jaw F will follow the movement of its jaw support under the action of the spring D¹⁶, as previously described.

At this point, it might be stated that the spacing member D¹⁴ between the disc D⁵ and the pulley D¹⁵ (see Fig. 12), by banking at its ends 10 against the top portion D⁷ of the fixed bracket D³, acts to limit the degree of movement of the disc D⁵ and the pulley D¹⁵ in both directions.

The third line of the group, constituting the return address, is also one to be centered with respect to the first or longest line and, as the first elevator descends with this line to locate it in casting position, the star wheel K is again rotated in a clockwise direction through a distance equivalent to one tooth on the ratchet wheel K³. 20 This movement of the star wheel, however, does not bring a prong into engagement with the slide actuating lever J⁴. Consequently, the slide J will maintain the machine conditioned, as in the previous cycle, with the result that this line will 25 also be centered with respect to the first quadded line, in the same manner as the second line of the group.

The next line to be cast will be the first line of a new group, but as the operations here will be 30 the same as for the first line of the previous group, nothing further need be said.

Since the present improvements contemplate that the right hand jaw F will be located to the left of its normal position when the first elevator 35 C descends to present the composed line between the jaws (as for instance, in casting those lines of a group which are centered with respect to the longest quadded line), it is obvious that the composed line can not be presented to the mold at the 40 right end thereof, as usual, since, if it were, the right hand jaw would interfere. Consequently, in the present machine, provision is made for presenting the composed line to the mold adjacent the left end thereof, since, throughout the operation 45 of the machine, the left hand jaw E will have a constant definite position at the beginning of each machine cycle. As shown in Figs. 1 and 2, the longer left hand finger B² of the line delivery carriage B, instead of being movable with respect 50 to said carriage, is, during the operation of the machine, locked to the carriage, although it is adjustable to the extent required to aline it with the left hand jaw for different settings of the latter when the carriage is in its leftmost position. However, once adjusted, it remains relatively fixed. The shorter right hand finger B³, instead of being relatively fixed as usual, is carried by a block B⁴ slidably mounted on the line delivery carriage, and the line and carriage are actuated to the left through mechanism connected to 55 said block, i. e., when the line is presented between the two fingers B² and B³, the right hand finger is moved to the left, pushing the line before it until the line, at its leading end, banks against the left 60 hand finger. Thereupon, the line pushes the left hand finger B², as well as the carriage B (the two being locked together), to the left until the carriage is arrested by banking at its left end against the usual banking screw B⁵. Since in this position 65 of the carriage, the left hand finger by preadjustment will be in alinement with the left hand jaw, the first elevator, upon descending to the casting level, will locate the line adjacent said jaw.

70 Since the composed lines will vary in length,

involving a corresponding variation in the movement of the right hand finger, provision is made for such varied movement in the delivery slide actuating mechanism. The mechanism includes the usual delivery starting lever B⁶ fastened to the usual delivery lever shaft B⁷, the movement of which acts to start the machine in the usual way. The lever B⁶ at its upper end is forked and spans a second lever B⁸ loosely mounted on the delivery lever shaft B⁷. The lever B⁸ at its upper end is 10 connected by a link B⁹ to another lever B¹⁰ pivotally connected at its upper end to the finger block B⁴ and, at its lower end, to a block B¹¹ arranged to slide in vertical guideways B¹² fixed to the machine frame. Assuming that the throw of 15 the lever B⁸ is fixed and sufficient to accommodate the full range of movement of the right hand finger B³, variations in line length will be compensated for by the lever B¹⁰, the lower end of which will take different positions, depending upon 20 the length of the composed line. There is a spring connection between the starting lever B⁶ and the lever B⁸ to cushion the parts and hold the delivery slide B firmly against the banking screw B⁵, there being sufficient overthrow between the 25 levers for this purpose, and at the same time allowing full motion of the lever B⁷ to effect starting of the machine.

A group of slugs Z cast with the present improvements is illustrated in Fig. 23. As shown 30 the slugs are of the fudge variety (the kind usually used for return address work), that is, they are formed with bevelled ends Z¹ to provide surfaces for securing them in a fudge box or in a recess provided in the printing cylinder for the purpose, 35 and are somewhat thinner at the base than at the casting edge so that when stacked, they will conform to the cylindrical surface of the printing member.

A fudge mold G, suitable for casting slugs of 40 the character just mentioned, is shown in Figs. 4 and 21, and includes, as usual, a body portion G¹ and a cap portion G² defining the lower and upper inclined side walls of the mold slot, and a pair of intermediate liners G³ defining the end walls of 45 the mold slot. The body portion of the mold is also provided at the front with an apron G⁴ presenting a horizontal rail G⁵ for cooperating with the lower projecting ears of the matrices during their alinement. The body and cap portions of the mold at the ends, as well as the intermediate liners, are formed with recesses G⁶, the inner ends of which are bevelled as at G⁷, and these recesses, during the casting operations, are closed by blocks G⁸ and G¹² formed with complementary bevelled portions for closing the mold slot at the ends in that portion thereof extending forwardly of the liners. The bevelled surfaces on the blocks form the bevelled ends Z¹ on the slugs 55 previously alluded to.

In the present instance and for the reason before stated, the blocks G⁸ and G¹² are fixed to the vise frame rather than to the line clamping jaws as heretofore.

The block G⁸ for closing the mold at the right 60 end is illustrated in Figs. 16, 19 and 22, and includes a horizontal body portion G⁹ complementary in shape to the recess G⁶ in the mold, a horizontal tongue G¹⁰ arranged to seat in a complementary groove F²¹ formed in the right hand 65 jaw F, and a vertical portion G¹¹ extending beyond the top of the jaw and bolted at its upper end to a fixed portion of the vise frame. The groove F²¹ extends substantially the full length of the jaw, so that the jaw can move relatively 70 75

to the fixed block. Consequently, regardless of the position the right hand jaw assumes during a quadding or centering operation, the block G⁸ will always be in position to seat in the recess in the mold and close the mold slot at the right. The block G⁸ is held in the groove in the jaw by a retaining plate F²², which, as shown best in Fig. 16, overlaps the tongued portion of the block and is held in place by a plurality of screws F²³ extending through the jaw and threaded into said plate.

The block G¹² for closing the mold slot at the left end (see Figs. 4 and 5) includes a body portion G¹³ with a bevelled face complementary to the bevelled faced recess in the mold, and a tongue G¹⁴ fitting into a complementary groove E⁵ in the left hand line clamping jaw E. The block is held against movement by a longitudinally disposed rod G¹⁵ passing through the groove E⁵ in the jaw and fastened at one end to the block G¹², and at its other end to a bracket E⁶ fixed on the vise frame. The rod G¹⁵ passes through the bracket E⁶ and is held in place by a nut G¹⁶ screwed on the threaded end portion of the rod and bearing against the bracket. This arrangement permits the block G¹² to be adjusted manually to accommodate molds of different sizes, it being understood that fudge molds of this character are usually somewhat shorter than the standard length molds.

As in the case of the right hand jaw groove F, the groove E⁵ extends substantially the full length of the left hand jaw, so that the jaw can move relatively to the block during a centering operation, while the block will always be in a position to close the mold slot at the end. Likewise, as in the case of the right hand jaw block G⁸, the block G¹² is retained in the groove in the left hand jaw by a retaining plate E⁷ fitted in the jaw and held in place by screws E⁸ passing through the jaw and threaded into said plate (see Fig. 5). In the case of both jaws, it will be noted that the grooves F²¹ and E⁵, which accommodate the tongued portions of the blocks, are disposed above the level of the mold slot to insure that the active faces of the jaws will close the mold slot at the front during the casting of a quadded or centered line.

Having described the improved machine, it is thought a clearer understanding of its operation can be gained from the diagrammatic illustrations of Figs. 24 to 30. In Fig. 24, the parts are shown at the conclusion of the casting of a group of slugs constituting a return address. The left hand jaw E, its jaw support E¹ and the right hand jaw support F¹ are in their normal positions, while the right hand jaw F is located to the left of its normal position, as determined by the longest quadded line of the group just completed.

A line P of matrices, constituting the longest line of the return address next to be cast, is now sent into the machine and presented between the line clamping jaws adjacent the left hand jaw E, the right hand jaw F at the beginning of the cycle having been returned to its normal right-most position. In Fig. 25, the parts are shown just before the quadding operation takes place. The line is now quadded, the right hand jaw and its jaw support being moved to the left until arrested by the banking of the jaw against the line, as shown in Fig. 26. After the casting operation takes place, the right hand jaw support is returned to its normal position, while the jaw itself is locked in the position in which it was arrested by banking against the line P, i. e., in its quadding position.

These relative positions of the parts are illustrated in Fig. 27.

With the parts thus relatively located, a second line P¹ of matrices is presented between the line casting jaws, adjacent the left hand jaw as before, and as it will be a shorter line than the first, there will be no question about its clearing the right hand jaw. It will be recalled that during the first part of the cycle in which the second line is presented in casting position, the machine is automatically conditioned for centering, while the jaw F is locked to its jaw support F¹, and then almost immediately released for simultaneous movement with its jaw support as the locking mechanism which held the jaw in its quadding position is rendered inoperative.

The machine now being conditioned for centering, both jaws are moved equi-distantly toward each other by their respective jaw supports until arrested by the banking of the jaws against the opposite ends of the composed line, but now because of the initial position of the right hand jaw at the beginning of this cycle, the line P¹ will be centered with respect to a new line u—u which, as will be observed, is offset to the left of the line v—v, the actual center line of the mold, the line u—u actually coinciding with a line through the center of the composed line of matrices P from which the previous quadded line was cast.

After the slug has been cast from the line P¹, the jaw supports E¹ and F¹ are returned to their normal positions, the left hand jaw E to its normal fully retracted position, but the right hand jaw F to a position somewhat to the left of its normal fully retracted position, since it remains locked to its jaw support F¹. This location of the parts is shown in Fig. 29.

A third composed line P² (Fig. 29) is now presented between the jaws E and F and which may or may not be shorter than the line P¹, although, of course, shorter than the first line P which, as previously stated, was the longest line of the group. During this cycle, the machine remains conditioned for a centering operation, and as the jaw E is still locked to its jaw support in the position determined by the longest quadded line P, the line P² will be centered with respect to the line u—u, or what is the same thing, centered with respect to said longest quadded line P (see Fig. 30).

The next line, being the first of a new group, the machine will be automatically conditioned for quadding, while the locking mechanism between the jaw F and its jaw support F¹ is rendered inoperative, allowing the jaw to return to its normal fully retracted position, which it does at once.

In the accompanying drawings, the invention has been shown merely by way of example and in preferred form, and obviously, many variations and modifications may be made therein which will still be comprised within its spirit. It is to be understood, therefore, that the invention is not limited to any specific form or embodiment, except insofar as such limitations are specified in the appended claims.

Having thus described my invention, what I claim is:

1. A slug casting machine including, in combination, left and right line clamping jaws, movable jaw supports therefor, means for adjusting the right hand jaw relatively to its movable jaw support to the left of its normal position, and means for locking the jaw to its support in its adjusted position.

2. A slug casting machine including, in combination, a slotted mold, a pair of line clamping jaws movable equi-distantly toward each other for quadding at the ends of a line, mechanism for effecting such quadding movement of the jaws, and means for adjusting the right hand jaw toward the left to permit offset centering to the left of the mold slot center line.

5 3. A slug casting machine including, in combination, a slotted mold, a pair of line clamping jaws movable equi-distantly toward each other for quadding at the ends of a line, jaw supports therefor, mechanism acting through the jaw supports for effecting such quadding movement of the jaws, and means for adjusting the right hand jaw to the left of its normal position on the jaw support to permit offset centering to the left of the mold slot center line.

10 4. A combination according to claim 3, wherein 20 means are provided for locking the right hand jaw to its support in its adjusted position.

15 5. A slug casting machine including, in combination, a slotted mold, a pair of line clamping jaws movable one toward the other for quadding at one end of a line or each toward the other for quadding simultaneously at both ends of a line, mechanism for effecting such quadding movement of the jaws, and means acting automatically to condition the machine to quad a 25 composed line at both ends in one machine cycle asymmetrically with respect to the mold slot in different positions depending upon the length of a line quadded at one end in a previous machine cycle.

30 35 6. A slug casting machine including, in combination, a pair of line clamping jaws movable one toward the other for quadding at one end of a line or each toward the other for quadding simultaneously at both ends of a line, mechanism 40 for effecting such quadding movement of the jaws, means acting automatically in one machine cycle to set the jaw active in quadding at one end of a composed line in a given location depending upon the length of said line, and 45 means for conditioning the machine to quad a line at both ends in a subsequent machine cycle without disturbing the set position of said jaw.

50 7. A slug casting machine including, in combination, a pair of line clamping jaws movable one toward the other for quadding and movable each equi-distantly toward the other for centering, mechanism for effecting such quadding and centering movement of the jaws, and means 55 acting automatically to condition the machine to center a composed line in one cycle with respect to a line quadded in a previous cycle.

8. A slug casting machine including, in combination, a pair of line clamping jaws movable 60 one toward the other for quadding and movable each equi-distantly toward the other for centering, mechanism for effecting such quadding and centering movement of the jaws, means acting automatically in one machine cycle to set the jaw active in quadding at one end of a composed line in a location coincidental with the 65 end of said quadded line, and means for conditioning the machine to move the jaws equi-distantly in a subsequent machine cycle without disturbing the set location of said jaw, to center a composed line with respect to the quadded line.

70 9. A combination according to claim 6, wherein the conditioning means is actuated automatically.

75 10. A combination according to claim 6, wherein the jaw automatically set in a location de-

pending upon the length of the quadded line is the right hand jaw.

11. A slug casting machine including, in combination, a pair of line clamping jaws, jaw supports therefor, means acting in one machine cycle 5 for automatically adjusting one of said jaws with respect to its jaw support to a given position depending upon the length of a composed line, and means for maintaining said adjustment of the jaw during casting in subsequent machine 10 cycles.

12. A slug casting machine including, in combination, a pair of line clamping jaws, jaw supports therefor, means acting in one machine cycle 15 for automatically adjusting one of said jaws with respect to its jaw support to a given position depending upon the length of a composed line, means for maintaining said adjustment of the jaw during a casting operation in a subsequent machine cycle, and means for automatically 20 restoring the jaw to its normal position after such casting operation.

13. A slug casting machine including, in combination, a pair of line clamping jaws, jaw supports therefor, means acting in one machine cycle 25 for automatically adjusting one of said jaws with respect to its jaw support to a given position depending upon the length of a composed line, means for maintaining said adjustment of the jaw during a casting operation in a subsequent 30 machine cycle, and means for automatically restoring the jaw to its normal position in still another machine cycle.

14. A slug casting machine including, in combination, a line clamping jaw, a support therefor, means for moving the jaw and jaw support as a unit to quad out a line at the end, and means for locking the jaw in its quadding position while allowing the jaw support to return to normal position.

35 15. A slug casting machine including, in combination, a line clamping jaw, a support therefor, means for moving the jaw and jaw support as a unit to quad out a line at the end, and means arranged on the vise frame for locking the jaw 45 in its quadding position while allowing the jaw support to return to normal position.

40 16. A slug casting machine including, in combination, a line clamping jaw, a support therefor, means for moving the jaw and jaw support 50 as a unit to quad out a line at the end, means acting during one machine cycle to lock the jaw in its quadding position while allowing the jaw support to return to normal position, and means for maintaining said relative positions of adjustment of the jaw and jaw support during a subsequent machine cycle.

55 17. A slug casting machine including, in combination, a line clamping jaw, a support therefor, means for moving the jaw and jaw support 60 as a unit to quad out a line at the end, means acting during one machine cycle to lock the jaw in its quadding position while allowing the jaw support to return to normal position, means for maintaining said relative positions of adjustment of the jaw and jaw support during a subsequent machine cycle, and means for releasing the jaw to permit simultaneous movement of the jaw and jaw support while thus adjusted.

65 18. A slug casting machine including, in combination, a line clamping jaw, a support therefor, means for moving the jaw and jaw support as a unit to quad out a line at the end, means arranged on the vise frame and acting during one 70 machine cycle to lock the jaw in its quadding position.

5 sition while allowing the jaw support to return to normal position, means for maintaining said relative positions of adjustment of the jaw and jaw support during a subsequent machine cycle, and means for releasing the jaw to permit simultaneous movement of the jaw and jaw support while thus adjusted.

10 19. A slug casting machine including, in combination, a line clamping jaw, a support therefor, means for moving the jaw and jaw support as a unit to quad out a line at the end, means acting during one machine cycle to lock the jaw in its quadding position while allowing the jaw support to return to normal position, means adapted 15 during a subsequent machine cycle automatically to couple the jaw and jaw support in their relative position of adjustment, and means likewise adapted during said machine cycle to release the jaw to permit simultaneous movement of the jaw and jaw support while thus adjusted.

20 20. A slug casting machine including, in combination, a pair of line clamping jaws, jaw supports therefor, one of said jaws being adjustable relatively to its jaw support, means for coupling 25 said jaw and jaw support in their different positions of adjustment, means acting through the respective jaw supports for moving the relatively adjustable jaw toward the other jaw for quadding at one end of a line, and for moving both jaws 30 equi-distantly toward each other for quadding at both ends of a line, mechanism for conditioning the machine for one quadding operation or the other, means controlled by the conditioning mechanism and adapted when the machine is 35 conditioned for quadding at one end of the line to adjust the jaw relatively to its jaw support by retaining said jaw in its quadding position as the jaw support is returned to normal position, means likewise controlled by the conditioning mechanism and adapted when the machine is 40 conditioned for quadding with both jaws to render the coupling means operative to couple the jaw with its jaw support in their adjusted positions, and means for rendering the jaw retaining means ineffective so as to permit simultaneous movement of the jaw and jaw support while thus 45 adjusted.

21 21. A slug casting machine including, in combination, a pair of line clamping jaws, jaw supports therefor, one of said jaws being adjustable relatively to its jaw support, means for coupling 50 said jaw and jaw support in their different positions of adjustment, means acting through the respective jaw supports for moving the relatively adjustable jaw toward the other jaw for quadding at one end of a line, and for moving both jaws equi-distantly toward each other for quadding at both ends of a line, mechanism for conditioning the machine for one quadding operation or the other, means controlled by the conditioning mechanism and adapted when the machine is 55 conditioned for quadding at one end of the line to render the coupling means inoperative and to adjust the jaw relatively to its jaw support by retaining said jaw in its quadding position as the jaw support is returned to normal position, means likewise controlled by the conditioning mechanism and adapted when the machine is 60 conditioned for quadding with both jaws to render the coupling means operative to couple the jaw with its jaw support in their adjusted positions, and means for rendering the jaw retaining means ineffective so as to permit simultaneous movement of the jaw and jaw support 65 while thus adjusted.

22. A combination according to claim 21, wherein means are provided for returning the relatively adjustable jaw to its normal position with respect to the jaw support when the coupling means is rendered inoperative in the event said jaw is in some position of adjustment other than normal.

23. A combination according to claim 20, wherein the means for effecting relative adjustment of the jaw and jaw support includes spring 10 pressed pawl devices operative when the machine is conditioned for quadding at one end of a line to retain the jaw in a position determined by the length of the quadded line while permitting the jaw support to return to normal position after 15 the quadding operation.

24. A combination according to claim 20, wherein the means for effecting relative adjustment of the jaw and jaw support includes a rotatable disk mounted on a fixed part of the machine and connected with the jaw for positive operation one by the other, and means operative when the machine is conditioned for quadding at one end of the line to lock the disk and consequently the jaw in one position or another as 20 determined by the extent of quadding movement of the jaw.

25. A combination according to claim 21, wherein the means for effecting relative adjustment of the jaw and jaw support includes a rotatable disk 30 mounted on a fixed part of the machine and connected with the jaw for positive operation one by the other, and means operating through the disk for returning the jaw to its normal position with respect to the jaw support when the coupling means is rendered inoperative in the event said jaw is in some position of adjustment other than normal.

26. A combination according to claim 20, wherein the conditioning mechanism is set for 40 conditioning the machine for quadding at one end of the line or at both ends of the line automatically according to a prearranged sequence.

27. A combination according to claim 20, wherein the conditioning mechanism includes a 45 shiftable slide adjustable to one position or another depending upon whether quadding at one end or at both ends of a line is desired, and automatic means for effecting the adjustment of said slide according to a prearranged sequence.

28. A combination according to claim 20, wherein there is provided automatic means for operating the conditioning mechanism to condition the machine for quadding at one end of the line or at both ends of the line according to 55 a prearranged sequence, said automatic means being actuated from the first elevator.

29. A combination according to claim 21, wherein the conditioning mechanism includes a device adjustable prior to the quadding movement of the jaws to one position or another depending upon whether the line is to be quadded at one end or at both ends, and means operated by said device for rendering the coupling means ineffective when said device is adjusted to condition the machine for quadding at one end of the line.

30. A combination according to claim 21, wherein the conditioning mechanism includes a device adjustable prior to the quadding movement of the jaws to one position or another depending upon whether the line is to be quadded at one end or at both ends, means operated by said device for rendering the coupling means ineffective when said device is adjusted to set the ma- 75

chine for quadding at one end of the line and for conditioning the jaw retaining means for operation, and means for operating the jaw retaining means after the quadding movement of the jaw has been completed.

31. A combination according to claim 21, wherein the conditioning mechanism includes a device adjustable prior to the quadding movement of the jaws to one position or another depending upon whether the line is to be quadded at one end or at both ends, and means controlled by said device and operable when the device is adjusted to condition the machine for quadding at both ends of the line to render the coupling means effective to couple the adjustable jaw and its jaw support together for operation as a unit.

32. A combination according to claim 21, wherein the conditioning mechanism includes a device adjustable prior to the quadding movement of the jaws to one position or another depending upon whether the line is to be quadded at one end or at both ends, and means controlled by said device and operable when the device is adjusted to condition the machine for quadding at both ends of the line to render the coupling means effective to couple the adjustable jaw and its jaw support together for operation as a unit, and to release the jaw restraining means in the event the latter has been active in effecting relative adjustment of the jaw and jaw support.

33. A slug casting machine including, in combination, a pair of line clamping jaws, one movable toward the other for quadding, mechanism to effect such quadding movement of the jaw, means for conditioning said mechanism for a quadding operation, devices for actuating the conditioning mechanism automatically during given casting cycles according to a prearranged sequence, and means including a periodically operated part of the machine for actuating said devices.

34. A slug casting machine including, in combination, a pair of line clamping jaws movable each toward the other for quadding at both ends of the line, mechanism for effecting such quadding movement of the jaws, means for conditioning said mechanism for a quadding operation, devices for actuating the conditioning mechanism automatically during given casting cycles according to a prearranged sequence, and means including a periodically operated part of the machine for actuating said devices.

35. A slug casting machine including, in combination, a pair of line clamping jaws movable one relatively to the other for quadding at one end of a line or each movable equi-distantly toward the other for quadding at both ends of the line, mechanism to effect such quadding movements of the jaw, means for conditioning said mechanism for quadding at one end of the line or at both ends of the line, means for actuating the conditioning mechanism automatically according to a prearranged sequence, and means including a periodically operated part of the machine for operating said devices.

36. A slug casting machine including, in combination, a pair of line clamping jaws movable one toward the other for quadding at one end of a line or each toward the other for quadding at both ends of the line, mechanism to effect such quadding movements of the jaws, means for conditioning said mechanism for one quadding operation or the other, and devices actuated by a periodically operating part of the machine for automatically setting the conditioning mecha-

nism to cast a plurality of groups of lines quadded at one end or at both ends according to a prearranged sequence.

37. A slug casting machine including, in combination, a pair of line clamping jaws movable one toward the other for quadding at one end of a line or each toward the other for quadding at both ends of the line, mechanism to effect such quadding movements of the jaws, means for conditioning said mechanism for one quadding operation or the other, and devices in the machine operable to set the conditioning mechanism automatically to quad in successive machine cycles a group of lines at one end or at both ends as desired, and adapted automatically in subsequent successive machine cycles to quad a group of lines at one end or at both ends in the same sequence.

38. A combination according to claim 35, wherein the devices for automatically actuating the conditioning mechanism includes a star wheel interchangeable with different star wheels depending on the prearranged sequence desired.

39. A slug casting machine including, in combination, an assembler wherein a line of matrices is composed, a vertically movable line transporter for presenting the composed line between a pair of line clamping jaws and in casting relation with the mold, an intermediate line delivery carriage for delivering the composed line from the assembler to the line transporter, and means associated with the line delivery carriage for locating the line, regardless of its length, in the line transporter in a position for presentation to the mold adjacent the left hand jaw.

40. A combination according to claim 39, wherein the line locating means associated with the line delivery carriage includes a relatively fixed left hand finger and a relatively movable right hand finger between which the composed line is located by the assembler, said left hand finger being located in alinement with the left hand jaw when the carriage is in line delivery position, and means for moving the right hand finger to push the line into contact with the left hand finger as the line is carried from the assembler to the line transporter.

41. A combination according to claim 39, wherein the line locating means associated with the line delivery carriage includes a relatively fixed left hand finger and a relatively movable right hand finger between which the composed line is located by the assembler, said left hand finger being located in alinement with the left hand jaw when the carriage is in line delivery position, and means for moving the right hand finger to push the line into contact with the left hand finger as the line is carried from the assembler to the line transporter, said means including a bar having a pivotal connection at one end with the right hand finger and having its other end adjustable to accommodate lines of different measure.

42. A slug casting machine including, in combination, a slotted mold recessed at the end, a block mounted independently of the mold and adapted to seat in said recess to close the mold slot at the end, and a relatively movable line clamping jaw cooperatively associated with said block for closing the mold slot at the front when lines of less than full measure are cast.

43. A slug casting machine including, in combination, a slotted mold recessed at the end, a block secured to a fixed part of the machine and adapted to seat in said recess to close the mold slot at the end, and a relatively movable line

clamping jaw cooperatively associated with said block for closing the mold slot at the front when lines of less than full measure are cast.

44. A combination according to claim 42, wherein the recess at the end of the mold is bevelled and wherein the block is complementally bevelled to fit.

45. A slug casting machine including, in combination, a slotted mold recessed at the end, a line clamping jaw, and a relatively fixed block portion adapted to seat in said recess to close the mold slot at the end and having a portion slidably fitted in said jaw, said jaw being movable relatively to said block for closing the mold slot at the front when lines of less than full measure are cast.

46. A slug casting machine including, in combination, a slotted mold recessed at its ends, a pair of blocks mounted independently of the mold and adapted to seat in said recesses to close the mold slot at the ends, and a pair of line clamp-

ing jaws movable one toward the other in quadrading and relatively with respect to said blocks.

47. A slug casting machine including, in combination, a slotted mold recessed at its ends, a pair of blocks secured to a fixed part of the machine and adapted to seat in said recesses to close the mold slot at the ends, and a pair of line clamping jaws movable equidistantly toward each other for quadrading at the ends of a line and relatively with respect to said blocks.

48. A slug casting machine including, in combination, a slotted mold recessed at its ends, a pair of blocks secured to a fixed part of the machine and adapted to seat in said recesses to close the mold slot at the ends, and a pair of line clamping jaws movable equi-distantly toward each other for quadrading at the ends of a line and relatively with respect to said blocks, said blocks being slidably connected to the jaws by interengaging tongue and groove portions.

RICHARD R. MEAD.
